(74) *Attorney, Agent, or Firm* — Fross, Zelnick, Lehrman & Sissu PC; Charles T. J. Weigell, Esq.

(57) **CLAIM**

The ornamental design for a brick with RGB lights, as shown and described.

DESCRIPTION

FIG. 1 is a front perspective view of the brick with RGB lights showing our new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines are for the purpose of illustrating portions of the brick with RGB lights that form no part of the claimed design.

1 Claim, 8 Drawing Sheets
